UNITED STATES PATENT OFFICE

2,511,662

PERMEABILITY TUNED LOOP ANTENNA CIRCUIT

William S. Bachman, Fairfield, Conn., assignor to General Electric Company, a corporation of New York

Application January 19, 1945, Serial No. 573,896

2 Claims. (Cl. 250—20)

1

The present invention relates to radio receivers and in particular to receivers which employ tuning of the resonant circuits by variations in the permeability of reactance elements thereof. It is an object of the present invention to provide a new and improved loop antenna circuit for a radio receiver which employs permeability tuning.

It is a further object of the present invention to provide a new and improved permeability tuned loop antenna circuit for a radio receiver which provides both a desirable tuning characteristic over a range of frequencies and a relatively high gain over that range. It is a still further object of the present invention to provide a new and improved low impedance loop antenna circuit employing permeability tuning which has a small amount of capacitive coupling with the electrodes of electron discharge devices employed in the circuit.

It is a still further object of the present invention to provide a new and improved permeability tuned loop antenna circuit which employs a transformer in which the overall coupling coefficient is maintained substantially constant throughout the tuning range.

It is a still further object of my invention to provide a new and improved loop antenna circuit for a radio receiver in which the necessity for shielding the antenna from the radio frequency circuits of the receiver is avoided.

The features of the invention desired to be protected herein are pointed out in the appended claims. The invention itself, together with further objects and advantages, may best be understood by reference to the following description taken in connection with the accompanying drawing in which Fig. 1 is a portion of a radio frequency circuit employing a permeability tuned loop antenna; Fig. 2 is a curve which shows the relation between the gain factor and the coupling between the primary and the secondary windings of the transformer used in the circuit of Fig. 1; Fig. 3 is a cross-sectional view of a transformer which may be employed in the circuit of Fig. 1; Fig. 4 is a modification of the transformer suitable for use in the circuit of Fig. 1; Fig. 5 is a curve showing the gain and tuning characteristic of the circuit of Fig. 1.

Referring to Fig. 1 of the drawing the portion of a radio frequency circuit there shown includes a loop antenna 1 which is connected in series with the primary winding 2 of a permeability tuned transformer 3. The transformer 3 includes a secondary winding 4 which is tightly

2

coupled to the primary winding 2 and which is tuned by means of a movable powdered iron core 5. The resonant circuit of the secondary winding 4 includes a capacitance 6 and the output terminal of the circuit is shown as connected to the control electrode of an electron discharge device 7.

In the construction of the circuit shown in Fig. 1 I have found that certain limitations on the circuit elements employed are desirable. In particular, it is desirable that both the loop antenna 1 be constituted by a few turns of wire and the primary winding 2 of the transformer comprise a small number of turns so that the capacitive coupling between the primary and secondary circuits is kept at a small value. It has been observed further that optimum results are obtained by closely coupling the primary winding 2 to the secondary winding 4 and by keeping the primary inductance substantially constant over the entire tuning range of the circuit so that the tuning range of the coupled circuits is substantially the same as that of the secondary circuit alone.

Furthermore, by so balancing the distribution of the primary circuit inductance between the loop antenna 1 and the primary winding 2, a maximum gain factor for the overall circuit may be obtained. The desired relation between the inductance of the antenna 1 and the primary winding 2 may be obtained from a consideration of the curves of Fig. 2 which show the variation of the gain factor

$$35 \quad \frac{\text{Gain}}{\sqrt{\frac{X_c}{X_{L_0}} Q_2}}$$

versus the overall coupling coefficient K of the entire primary circuit to the secondary winding.

40 This coefficient has a value equal to

$$\frac{M}{\sqrt{L_1 L_2}}$$

45 The circuit values used in arriving at the curves of Fig. 2 are:

$L_1 = L_0 + L_p$, i. e., the total inductance of the primary circuit,

L_0 =inductance of loop 1,

50 L_p =inductance of primary winding 2,

L_2 =inductance of secondary winding 4,

X_c =reactance of capacitor 6,

X_{L_0} =reactance of loop 1,

M =mutual inductance of transformer 3,

55 Q_2 =quality of secondary circuit.

In general, the maximum realizable coupling K_1 between the primary winding 2 and the secondary winding 4 should be employed, where

$$K_1 = \frac{M}{\sqrt{L_p L_2}}$$

The required value of L_2 is found from the range of frequencies to be covered, the value of capacitive reactance in the secondary circuit, and the overall coupling coefficient, i. e.,

$$X_{L_2} = \frac{X_c}{(1 - K^2)}$$

In arriving at this value of L_2 , it has been found that the quality Q_1 of the primary circuit has substantially small effect on the value of K , the overall coupling coefficient, to be used.

Starting with a suitable value for L_0 , which for a low impedance input circuit is a small inductance, for maximum gain in the antenna circuit the total inductance L_1 is distributed between the inductance L_0 of loop 1 and the inductance L_p of primary winding 2 by making L_p of the same order and slightly less than L_0 . The optimum ratio of these component inductances is obtained from the equation

$$\frac{L_p}{L_0 + L_p} = \frac{K^2}{K_1^2}$$

In order to maintain the gain at a maximum value over the entire frequency range of the receiver circuits, the value of the primary inductance L_p is maintained substantially constant as the resonance frequency of the secondary circuit is varied by adjustment of the tuning core 5.

In Fig. 3 there is shown one form of transformer suitable for use in the circuit of Fig. 1 and in which the inductance of the primary winding 2 is maintained at a low value and is kept substantially constant over the entire tuning range of the circuit. In this transformer structure, the secondary winding 4 is wound as a solenoid on a dielectric form 8 and the primary winding 2 is wound on one end of the tuning core 9, formed of compressed powdered iron particles. The core 9 at its left-hand end has a shoulder portion 10 upon which the primary winding 2 is wound. It has been found in the use of a transformer of this construction that, as the tuning of the secondary circuit is varied over its complete range, the inductance of the primary circuit is maintained substantially constant and that the coupling coefficient of the primary circuit is likewise maintained substantially constant.

Fig. 4 illustrates another form of the transformer construction which is suitable for use in the circuit of Fig. 1. In this transformer arrangement, the secondary winding 4 is a closely wound solenoid supported on a dielectric form 11 and the primary winding 2 is wound adjacent to the secondary winding on the form 11 at the end into which the tuning core 12 enters. It has been found that in the use of this particular form of transformer the inductance of the primary circuit varies by about 2:1, depending upon the position of the core 12, and the tuning range of the circuit is extended by allowing the core 12 to pass out of the primary coil 2 and lie wholly within the secondary coil 4.

Fig. 5 illustrates the gain and tuning characteristics of the circuit of Fig. 1 employing the transformer construction shown in Fig. 3. In the circuit having the characteristics indicated by the curves of Fig. 5, the inductance of winding 4 with the tuning core completely removed

was approximately 142.4 microhenries, the inductance of the winding 2 was one microhenry, the inductance of the loop antenna 1 was 2 microhenries, and the capacitor 6 had a value of 58 mmfd. In Fig. 5 curve 13 shows that the gain characteristic of the circuit as its tuned frequency is varied over the normal broadcast range by displacement of the position of the core 9 within the winding 4 is at all points quite high and has an overall variation of not more than 2:1. Curve 14 shows the displacement of the core with frequency and illustrates the tuning characteristic of the circuit.

While the invention has been described by reference to a particular embodiment thereof, it will be understood that numerous modifications may be made by those skilled in the art without departing from the invention. I therefore aim in the appended claims to cover all such equivalent variations as come within the true spirit and scope of my invention.

What I claim as new and desire to secure by Letters Patent of the United States is:

1. In a radio receiver, the combination of a loop antenna, a transformer having a primary winding serially connected with said antenna, said transformer comprising a tubular dielectric member, said primary winding being supported on said member, a secondary winding supported on said member closely adjacent said primary winding and closely coupled therewith magnetically and so arranged that the capacitive coupling therewith is minimized, and a magnetic core movable within said member and magnetically coupled to both of said windings for varying the inductance of said secondary winding while maintaining the inductance of said primary winding substantially constant, said primary winding having an inductance of the same order of but less than the inductance of said loop antenna.

2. In a radio receiver, the combination of a loop antenna, a transformer having a primary circuit comprising a primary winding serially connected with said antenna, said transformer having a secondary winding closely coupled to said primary winding, the inductance of said primary winding to the inductance of said primary circuit being proportional to

$$\frac{K^2}{K_1^2}$$

where K and K_1 are the coupling coefficients of said secondary winding to said primary circuit and said primary winding respectively, and means comprising a movable core member magnetically coupled to both of said windings for varying the inductance of said secondary winding while maintaining the inductance of said primary circuit and said primary winding substantially constant.

WILLIAM S. BACHMAN.
